UNITED STATES PATENT OFFICE.

CHARLES WESLEY ALLEN, OF MERRIMAN, NEBRASKA.

LETTER-BINDER.

No. 905,829.

Specification of Letters Patent.

Patented Dec. 8, 1908.

Application filed December 9, 1907. Serial No. 405,790.

To all whom it may concern:

Be it known that I, CHARLES WESLEY ALLEN, a citizen of the United States, residing at Merriman, in the county of Cherry and 5 State of Nebraska, have invented certain new and useful Improvements in Letter-Binders; and I do hereby declare the following to be a full, clear, and exact description of the invention, such as will enable others 10 skilled in the art to which it appertains to make and use the same.

My invention relates to improvements in letter binders, the object of which is to press, bind and carry letters and other mail matter 15 through the mail without the use of twine or string of any kind.

The invention consists broadly of two bows pivoted at opposite ends of a bottom or back piece, and a rack bar adapted to be 20 engaged by the free ends of said bows whereby the mail matter is clamped between said rack bar and back piece.

The invention further consists in the features of construction and combinations of 25 parts hereinafter described and specified in the claims.

In the accompanying drawing, illustrating the preferred embodiment of my invention: Figure 1 is a perspective view of the binder as 30 in use with a pile of letters secured therein. Fig. 2 is a plan view of the binder with the rack bar removed. Fig. 3 is an end view thereof. Fig. 4 is a detailed section of a portion of a modified construction of rack bar 35 having disappearing spring teeth or ratchets, and Fig. 5 is a side view of the binder in an inverted position and resting upon the rollers as when the letters are being compressed and the free ends of the bows brought into engagement with the proper teeth on the rack 40 bar.

Referring more particularly to the drawing, 1 designates the bottom or back piece which is preferably made of wood to economize weight. The bows 2 and 3 are hinged or pivoted to the ends of said back piece in any suitable manner such as the bent or looped strips 4 passed around the interlocking ends of the parts of the bows. Said bows are preferably made of light but strong 45 steel wire and are laterally extensible to fit different sizes of letters, papers, etc. As shown in the drawing, each bow is made of two pieces of wire having their ends overlapping each other and their extremities bent or looped around, and adapted to slide on the

opposite piece, as indicated at 5. In lieu of this construction, the desired lateral adjustment of the bows may be obtained in any other suitable manner.

The rack bar 6 should preferably be made of wood to save weight but it may also be made of light metal. Instead of the integral teeth shown in Fig. 1, said teeth may be mounted on plates 7 arranged on springs 8 60 in sockets or chambers 9 in the rack bar, as illustrated in Fig. 4. It is obvious that said toothed plates 7 will be depressed as the ends of the bows pass over them during the clamping or binding operation and that the 65 springs 8 will raise said plates after each tooth is passed until said bows are finally engaged by the desired teeth.

On the free end of each of the bows are mounted rollers 10 which facilitate the binding operation. When the letters have been placed in the binder and the bows crossed, the device is turned over and, pressure being exerted by the hand upon the back piece, the rollers carry said bows out to the proper 80 notch or tooth. The rollers, however, are not a necessary feature of the invention as the binding or clamping may be accomplished when the device is in an upright position by placing the end of one of the bows in 85 a notch in the rack bar and pulling the end of the other bow until it engages the proper notch.

I claim:

1. A binder of the character described, 90 comprising a back piece, a plurality of laterally extensible bows each composed of two parts having their ends slidably interlocked with each other, each of said bows being pivoted to said back piece by having the interlocking portions of its parts loosely inclosed 95 in a loop secured to said back-piece, and a rack bar adapted to be engaged by said bows for the purpose specified.

2. A binder of the character described, 100 comprising a back piece, a plurality of laterally extensible bows each composed of two parts having their ends slidably interlocked with each other, each of said bows being pivoted to said back piece by having the interlocking portions of its parts loosely inclosed 105 in a loop secured to said back-piece, and a rack bar adapted to be engaged by the other interlocking portions of said bows for the purpose specified.

3. A binder of the character described, 110 comprising a back piece, a plurality of bows

pivoted to said back piece, rollers mounted on the free ends of said bows, and a rack bar adapted to be engaged by said bows for the purpose specified.

5. 4. A binder of the character described, comprising a back piece, a plurality of bows pivoted to said back piece and a rack bar having spring pressed disappearing teeth

adapted to be engaged by said bows for the purpose specified.

10

In testimony whereof, I affix my signature, in presence of two witnesses.

CHARLES WESLEY ALLEN.
